UNITED STATES PATENT OFFICE.

ALEXANDER J. LUNSER, OF LONG PRAIRIE, MINNESOTA.

LADDER-FOOT.

1,300,430.

Specification of Letters Patent. Patented Apr. 15, 1919.

Application filed February 25, 1916. Serial No. 80,444.

To all whom it may concern:

Be it known that I, ALEXANDER J. LUNSER, a citizen of the United States, residing at Long Prairie, in the county of Todd and 5 State of Minnesota, have invented certain new and useful Improvements in Ladder-Feet; and I do hereby declare the following to be a full, clear, and exact description of the invention, such as will enable others 10 skilled in the art to which it appertains to make and use the same.

This invention relates to new and useful improvements in a ladder foot and one of its objects is the provision of a device of 15 this character, which shall be simple, durable and efficient, and which may be manufactured and sold at a comparatively low cost.

Another object of this invention is to 20 provide a ladder foot adjustably secured to each of the ends of the upright rails of a ladder, whereby either of the feet may be adjusted away from the ends of the ladder horizontally so as to support the ladder 25 horizontally upon uneven ground.

A further object of this invention is to provide brackets secured to the upright rails of the ladder to receive adjustable bars, having a plurality of rack teeth to be 30 engaged by a cam lever carried by one of the brackets to lock the bars at any desired position.

A still further object of this invention is the provision of feet extending at right 35 angles to the bars to form rests for the ends of the upright rails of the ladder when not being employed upon uneven ground which will prevent the ends of the upright rails, which are usually constructed of wood, from 40 becoming worn or mutilated.

With these and other objects in view as 45 will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a fragmentary front elevation 50 of a ladder illustrating the ladder feet secured thereto, constructed in accordance with my invention,

Fig. 2 is a fragmentary side view of one

of the upright rails of a ladder, illustrating my invention applied thereto and in an extended position,

Fig. 3 is a horizontal sectional view of one 60 of the brackets, taken on the line 3—3 of Fig. 2, and

Fig. 4 is a horizontal sectional view of the other bracket taken on the line 4—4 of 65 Fig. 2.

Referring in detail to the drawing, the numeral 1 indicates a ladder consisting of upright rails 2 and 3, connected together by rungs 4, to which my invention is applied.

Secured to the upright rails 2 and 3 by 70 nuts 6 are bolts 5, having plates 7 formed on the outer end. A substantially U-shaped plate 8 is formed on each of the plates 7 and slidably receives adjusting bars 9, having a plurality of rack teeth 11 formed on 75 one edge thereof. Cam levers 12, having handles 13 and enlarged portions 14 are pivoted to each of the U-shaped plates at one side of the plates 7 by bolts 15. The enlarged portions 14 engage within the teeth 80 11 of the rods 9 when the cam levers 12 are swung inwardly toward the plates 7 as illustrated in Fig. 3, to lock the bars at various positions.

Secured to the lower ends of the upright 85 rails 2 and 3 of the ladder 1 by nuts 17 are bolts 16 having plates 18 formed on the outer end thereof, a substantially U-shaped plate 19 is formed on each of the plates 18 to receive the bars 9 and support them in 90 parallel alignment with the lower ends of the upright rails 2 and 3.

Formed on and extending at right angles 95 to the bars 9 are feet 20. The feet 20 act as efficient rests for the upright rails 2 and 3 of the ladder 1, when in an extended position or when in engagement with the ends of the upright rails 2 and 3, and in this position the feet 20 prevent the ends of the upright rails from becoming worn by resting upon the ground or from being dragged upon the ground when moving the ladder from one place to another.

In operation, when the ladder 1 is to be 105 employed upon uneven ground, which frequently occurs around buildings and such places, one of the bars 9 is extended by swinging the respective cam lever 12 upon its pivot until the enlarged portion 14 disengages the teeth 11. The bar 9 is then extended until the foot carried thereby comes 110 in contact with the ground and the cam lever

13 is then swung back to its normal position, which holds the bar 9 against upward and downward movement in relation to the upright rails to which it is applied. The up- 5 right rails 2 and 3 will then be supported evenly as if resting upon level ground as clearly illustrated in Fig. 1; thus the ladder may be ascended by a person without the danger of its slipping or falling from en- 10 gagement with the building or other object against which it is resting.

The cam levers 12 are pivoted to the under sides of the housings 8, and are arranged at right angles with relation to the rack 15 bars 9. When the cam levers 12 are in active or bar securing position, they extend transversely across the rack teeth 11 and lie in engagement with the under sides of the housings 8. As the cam levers 12 engage 20 the under sides of the housings 8 when in active position, the force acting upon the cam levers, due to the weight of the ladder and its occupant or occupants, is not borne by the pivots of the cam levers but by the 25 housings. This obviates all liability of damage to the pivots, and prevents the accidental disconnection of the cam levers from the housings during the use of the ladder. The cam levers also, when in active position, 30 engage between pairs of the rack teeth 11 and hold the bars against any upward or downward movements with relation to the ladder. This permits the ladder to be shifted

without danger of the rack bars becoming out of adjustment.

While I have shown and described the preferred embodiment of my invention, it will be understood that minor changes in construction, combination and arrangement of parts may be made without departing 40 from the spirit and scope of the invention as claimed.

Having thus described my invention, what I claim is:—

An adjustable foot for ladders comprising 45 in combination with a ladder housings secured to one side rail of the ladder, a rack bar adjustably mounted in the housings and provided with a foot, and a cam lever pivoted to the under side of one of the housings and arranged at right angles with relation to the rack bar, said cam lever being adapted to be swung transversely across the rack teeth to secure the rack bar in adjusted 50 position against upward or downward movements with relation to the ladder, and said cam lever being adapted when in rack bar securing position to engage the under side of the housing.

In testimony whereof I affix my signature 60 in presence of two witnesses.

ALEXANDER J. LUNSER.
